UNITED STATES PATENT OFFICE.

URI HASKIN, OF PITTSBURG, PENNSYLVANIA.

ROLLING-MILL.

SPECIFICATION forming part of Letters Patent No. 269,573, dated December 26, 1882.

Application filed May 22, 1882. (No model.)

To all whom it may concern:

Be it known that I, URI HASKIN, a citizen of the United States, residing at Pittsburg, in the county of Allegheny and State of Pennsylvania, have invented certain new and useful improvements in Rolling Metals; and I do hereby declare the following to be a full, clear, and exact description thereof, reference being had to the accompanying drawings, forming a part thereof, in which—

Figure 1 on Sheet 1 indicates a front elevation of a set of vertical rolls mounted in sectional housings, which are constructed and arranged in such a manner as to allow the upper sections to be swung open and shut upon their pivotal connection with the lower section of the housings. These upper sections are provided with a hydraulic ram, connected to them by means of intermediate mechanism, adapted to remove the detachable cap-piece from the head of the housings and to replace it in position, and to impart a lateral swinging movement to the upper sections upon the lower. The housings are also provided with balancing-weights, which are so arranged in relation to the upper sections of the housings as to cause them to swing back again into working position after being opened and the action of the ram and its connections upon them has ceased. Fig. 2 on Sheet 2 indicates a side elevation of the same. Fig. 3 on Sheet 3 indicates a front elevation of a set of horizontal rolls mounted in sectional housings, which are separable at or near a plane passing between the working-faces of the rolls, and the upper roll is so arranged in relation to the upper section that the former may participate in any vertical movement imparted to the latter. The two sections of the housings are provided with locking-clutches which engage in recessed portions of the lower housings, and are also provided with a hydraulic ram, which operates the locking-clutches and throws them into and out of position to engage the lower section, and also removes and replaces the upper section. Fig. 4 on Sheet 4 indicates a side elevation of the same. Fig. 5 on Sheet 5 indicates a plan view of the horizontal-roll housings. Fig. 6 on Sheet 5 indicates a side elevation of the same, showing the locking-clutches released or their lower ends withdrawn from the rectangular slots formed in the upper part of the inner faces of

the lower section of the housing, and illustrates the mode of raising the upper from the lower section of the housing. Fig. 7 indicates a front elevation of the vertical rolls, their sectional housings, and hydraulic mechanism for swinging the upper sections when the latter have been swung open on the pivots connecting them with the lower section of the housings. Fig. 8 on Sheet 7 indicates a side elevation of a portion of a continuous rail-train, showing the arrangement of the series of sectional housings and their hydraulics arranged so that several sets of rail-rolls may operate upon the metal at one and the same time.

Like letters of reference indicate like parts wherever they occur.

The object of my invention is to uniformly produce rails having sound solid flanges.

Heretofore it has been impossible to produce rails with good solid flanges, free from cracks, unless a special quality of iron was put into the pile to form the finished flanges, and even in such cases, and where the greatest care and skill were used in rolling, it was frequently found that the flanges of the rail-blank cracked during its reduction, and especially so during the last few passes of the rolling operation. The same difficulty has also existed in the manufacture of steel rails, and has prevented the use of various grades of steel for such purpose. In investigating this matter I have observed that in the reduction of the bloom or pile into the rail the portion of the metal which forms the flange loses its temperature much faster than that of the body of the rail, in fact sometimes running out at almost a black heat while the head of the rail was red-hot, this fact being due to the great surface of the flange when compared with its transverse section, and of the comparatively small surface of the head in comparison with the head's cross-section, allowing them to lose their heat unequally in any given time. This variation of temperature affords the basis for the explanation of the difficulty, because it is evident that when subjected to any given pressure the tendency of the metal to flow through the groove depends upon its degree of heat, being great at a high and low at a low temperature. Therefore in such cases the metal in the head flows faster than is the tendency of the metal in the flange, and either causes its rupture or

leaves permanent rupturing strains in the rail. Another difficulty in the manufacture of rails by the ordinary rolling operation is that all the rail-forming grooves are placed in the same 5 set of rolls, and although some qualities of iron may be found to work comparatively well, others will crack in the flange during the last few passes, because the draft there is too great or too little for such qualities, and in such cases 10 the evil cannot be avoided without turning the rolls to suit the particular quality of metal, because the draft of the entire set of grooves must be adjusted at the same time.

To the end, therefore, that all the preceding 15 difficulties may be avoided and a better, cheaper rail produced, I propose, first, to provide but one pass to each set of rolls, in order that the degree of reduction at each pass may be varied to suit different qualities of metal; secondly, 20 to arrange a series of cogging and rail-reducing rolls in line and in close proximity with each other, so that several or all the sets may operate upon the metal at one and the same time and reduce the bloom or pile into a finished rail before the temperature of the flange 25 can be sensibly reduced below that of the head of the rail; thirdly, to either drive each succeeding set of rolls at a little less rate of speed than the metal tends to flow out of the delivery 30 side of the groove of the preceding set, or to adjust the successive sets by means of the roll-tightening screws so that their rotary action is not quite sufficiently fast to enable them to draw all the metal into their grooves 35 as fast as it is delivered by the preceding set, in which case, (as in the former,) each preceding set is compelled to assist the metal by shoving it at a little faster speed than is its natural tendency to pass through the succeeding groove, the object being to avoid all 40 drawing or pulling of the metal between the different sets and to exert a back-pressure upon the metal to overcome the tendency of the metal in the head to flow fast and drag 45 the flange with it through the grooves, which, on account of the lower temperature and lower ductility of the metal there, causes the fractures or cracks in the flange.

I shall now describe my invention and the 50 mechanism which I use in carrying it into effect more fully, so that others skilled in the art to which it appertains may make and use the same.

In the drawings, A indicates the driving-shaft of one set of the vertical rolls. This driving-shaft is located beneath the mill-floor, and is suitably journaled in a set of pillow-blocks, B B, which rest upon suitable foundations, and extend back under and support the 60 bed-plates B' B', upon which the lower section, C, of the housings is mounted, and this section C is bolted permanently to the bed-plates B' B', so as to be incapable of any movement, and is provided at the front and back of its sides 65 with journal-boxes c c for the reception of the journals of the shafts or pivots c' c', which con-

nect the upper with the lower sections of the housings. These shafts or pivots c' c' pass through and are keyed permanently into the downwardly-projecting portions of the sides of 70 the upper sections of the housings; or the shafts may be made square at those points and be fitted into rectangular slots in the upper sections, or be attached thereto in any other suitable manner, to cause the upper sections to swing into 75 and out of working position when the shafts are oscillated by means of their actuating mechanism. Each of the shafts or pivots c' are provided at both ends with oscillating cranks c² c², which are operated by means of a set of crank-rods, c³ c³, which are pivoted at their upper ends to the ends of the cross-heads c⁴ c⁴, which are perforated or provided with sleeves at their center to allow the lifting-rods d d of the hydraulic ram D to pass through without communicating motion to them until the action of the lifting-rods d d elevates the adjustable detachable housing-cap d' clear off of the head of the upper sections of the housings and forces its upper surface up against the lower surface 80 of the cross-heads, when they participate in the vertical movement of the lifting-rods and impart an upward movement to the crank-rods, which, by actuating the cranks and housing-pivots, then cause the sections to swing open 85 into the position shown in Fig. 7. The adjustable detachable housing-cap is attached to the lifting-rods d d, so as to become elevated as soon as any movement is imparted to them by the action of the hydraulic ram, and it is 90 formed of a cast-iron rectangular box, open at the bottom, and the front, back, top, and one side cast in a solid piece, and the remaining side is formed of an iron plate hinged or pivoted to the top of the open side of the box, so that the 95 lower part of the plate may be adjusted inwardly to take up any slack between the sections of the head of the housings.

E indicates a wrought-iron band (which with the housing-cap is shown in section, or with the front portion removed to show the face of the head of the upper housings or sections) surrounding the housing-cap, and is provided with a suitable adjusting-screw, e, to force the breaker e' against the lower part of the adjustable iron plate d² or adjustable side of the housing-cap, the object being to allow the cap to be tightened up to fit the housings-head and to remove the strain from the cap to the band during the rolling operation, the breaker being 110 used to prevent any serious strain from coming upon the mechanism by giving away or breaking to relieve the pressure upon the metal.

The driving-shaft A is provided with a set of beveled-gear wheels, a a, which mesh into 115 and communicate motion to the beveled-gear wheels a' a', mounted on the lower ends of the vertical spindles, which drive the lower sections, F F, of the coupling-clutches, and these vertical driving-spindles are mounted or have 120 their bearings in the vertical sleeve-boxes a² a², which are let down into the lower section

of the housings, and may be adjusted into position to adapt the spindles for driving the clutches for varying sizes of rolls by means of the adjusting-screws a^3 a^3 and a^4 a^4 a^4 a^4 .

5 F' and F' indicate the upper sections of the coupling-clutches, which are keyed securely onto the lower ends of the spindles of the rolls, and both the upper and the lower sections of the coupling-clutches are provided with ratchet-teeth inclining at a sufficient angle in the direction in which the upper sections of the housings are to swing as to allow a ready connection and disconnection of the clutch-sections during that operation.

15 G G G G indicate adjusting-screws for imparting lateral adjustment to the vertical rolls. H and H' indicate the roll-guides, which are vertically adjustable by means of the adjusting-screws h h , which operate in threaded 20 bearings in brackets on the front of the upper housings-sections, and operate against the lower sides of the guides, and the guides are adjusted laterally by means of the lateral adjusting-screws h' h' .

25 d^3 indicates the inlet and outlet water-pipe of the hydraulic ram, and d^4 and d^5 indicate the inlet and outlet valves, respectively.

30 J J indicate a set of weights, which are suspended below the mill-floor by means of chains attached to the ends of the cranks of the pivots of the upper sections of the housings. The object of this arrangement is to have a sufficient counter-weight connected with the upper sections to compel them to swing again back 35 into position when they have been opened and the action of this opening mechanism upon them has ceased.

In Figs. 3, 4, and 6, where a set of horizontal rolls mounted in sectional housings are 40 shown, the construction and arrangement of the hydraulic cylinder, plunger, and its inlet and outlet pipe and valves are the same as in that of the vertical rolls; but the construction of the housings and the mode of separating them are somewhat different.

45 K K indicate the foundation-plates, and k k the bed-plates bolted thereon.

L indicates the lower and L' the upper section of the housings, which are so constructed 50 as to be capable of separation at or near a plane passing between the working-faces of the rolls.

55 M and M indicate a set of locking-clutches, which are pivoted at their centers in recesses in the inner faces of the upper sections of the housings, and are attached at their upper ends to the lifting-rods of the hydraulic. The lower portions of these locking clutches M and M are provided with lateral projections m m , adapted 60 to engage in rectangular slots formed in the inner faces of the lower section of the housings, in order to lock the sections during rolling and to release them when it is desired to elevate the top roll and housings section. The 65 housings are also provided with a similar set of locking-clutches, attached at their rear and

operated by another set of lifting-rods attached to the hydraulic.

N indicates the top guide, n indicates its vertical adjusting guide-rod, and n' indicates 70 a screw for adjusting it to and from the face of the upper roll.

M' indicates the bottom guide, and n^2 the lower guide-adjusting screw.

O indicates the driving-spindle of the lower 75 roll, and P P' indicate the gearing for the transmission of motion from the lower to the upper roll.

S indicates a steel spring inserted between the upper and lower journal-boxes at each end 80 of the housings, and serves to maintain the top roll up off of the lower when the metal is not between their faces, the object being to avoid the shock, jar, and strain to which the mechanism would be subjected if the top roll were 85 allowed to drop after the passage of the metal.

T and T indicate the tightening or roll-adjusting screws, and t t indicate breakers, which are inserted between the top journal-boxes and the lower ends of these screws. 90

v v indicate tightening screws, which work in threaded bearings sunk in the sides or ends of the upper sections of the housings. The object for which these screws are used is to provide means for forcing the top journal-boxes 95 against the ends of the top roll until the friction and pressure of the screws against the inner sides of the flanges of the boxes are sufficient to retain the roll and boxes in position in the upper section of the housings during 100 the removal of one section from the other.

In the arrangement of a continuous train for rolling rails from blooms at a single heat and rolling operation the arrangement will depend somewhat upon the size of the bloom, the degree of reduction to be effected at each pass, and upon the size of the rail to be produced. For rolling seven inch billets it will be about as follows: first set of rolls, horizontal; second, vertical; third and fourth, horizontal; 105 fifth, vertical; sixth, horizontal; seventh, vertical; eighth, horizontal; ninth, horizontal; tenth, vertical; eleventh, twelfth, and thirteenth, horizontal. The grooves in the first five sets of rolls correspond with those in the ordinary cogging-mill, and reduce the bloom into the proper size billet or rail-blank to enter the rail-forming rolls proper, which in the above arrangement would commence at the sixth set, and the remainder of the rolls are 110 provided with a form of groove to correspond with the form of groove used for corresponding grooves in an ordinary set of rail-rolls, so that the train may be adapted to reduce the bloom or pile into a finished rail at a single 115 continuous pass, the object being, as before stated, to bring out the finished rail before the temperature of the flange can fall sufficiently below that of the head to crack the flange or leave permanent rupturing strains in the bar 120 at that portion.

125 As previously stated, the arrangement of the

horizontal and vertical rolls will vary somewhat, and therefore I do not intend to restrict myself to any particular arrangement of horizontals and verticals, or to any particular form 5 or number of sets of rail-rolls, as long as they are so arranged as to reduce the bloom or pile into the rail before the flanges can be cooled down to a point where breaking strains can come upon them. In the arrangement of the 10 rail-rolls proper from the sixth pair to the last in the train the tongued and grooved horizontal rolls are reversed in each succeeding pair of horizontal-roll housings—that is to say, the grooved rolls will be in the lower section of 15 the sixth set of housings and in the upper section of the next set of horizontal-roll housings, and alternate in like manner from the lower to the upper sections in the succeeding horizontal housings of the train—the object of this 20 arrangement being to cause the fin (which forms up against the edges of the tongue) to pass into and be rolled down in the bottom of the groove of the next set of horizontals. The continuous rail-train should be adjusted so 25 that the surface speed of each successive set of rolls should be slightly less than that of the metal as it emerges from the delivery side of the preceding set—that is to say, assuming the reduction to be equal at each pass to twenty per cent. of the transverse area of the metal 30 operated upon, the metal would deliver twenty per cent. faster than it would enter each or any one set of rolls. Now, in ordinary practice it has been usual to provide an increase 35 of twenty per cent. in speed for each successive set over its preceding sets where such a degree of reduction took place, in order that any set could draw in the metal at as fast a rate as it was delivered by the set immediately 40 preceding; but in the present case I propose to provide, say, from one-half to one and one-half per cent. less than the total speed required to draw the metal in as fast as delivered by the preceding set, or to construct the 45 train with the usual allowance for the increased speed of each successive set, and then adjust the rolls of each successive sets by means of their tightening-screws, so that the metal may be delivered a little faster by each preceding 50 set than it can be drawn into the succeeding set, the result in either case being that the action of each preceding set helps to shove the metal through its succeeding set, and by jamming or upsetting it between each set not 55 only relieves it from all strain by the rolls upon the flange, but the back-pressure holds the hotter metal in the head back and prevents it from flowing faster and tearing the flange.

In the practice of my improvement a series 60 of sets of rolls mounted in sectional housings and provided with a hydraulic lift (or in lieu thereof any cylinder provided with a piston adapted to be moved by fluid-pressure) for each set of housings may be used, and may be arranged in close proximity to and in line with each other, so that several or all the sets of

rolls may operate upon the metal at one and the same time. For bar iron and steel the train may consist of alternate sets of horizontal and vertical rolls, if desired, the grooved 70 and tongued rolls alternating from the bottom to the top sections of the horizontal-roll housings, as before described, and alternating from one side to the other in the vertical sectional roll-housings, so as to bring the fin formed by 75 the collar of one set of horizontals into the bottom of the groove of the next set of horizontal rolls, and to bring the fin formed by the collar of one set of verticals down into the bottom of the groove of the next set of vertical 80 rolls; but in cases where it is desired to make use of the mechanism for rolling rails where the verticals are only used—as edging or “dummy” or “swabbing” rolls—the grooved rolls of the vertical-roll housings are not alternated 85 from one side or housing-section to the opposite, as in the case last mentioned.

In the operation of my improvement, the train being arranged as before described, and having the rolls adjusted to reduce the metal 90 to the proper degree to give a slight back-pressure upon the metal in its passage from the preceding to the succeeding sets, a properly-heated pile or bloom is inserted within the groove of the first set, passes through and 95 is rolled down by the first five sets into the form of billet or rail-blank produced by the ordinary cogging-mill, and the blank then enters the sixth set and passes rapidly through the remaining sets, coming out in the form and section of rail desired, free from cracks in the flanges and the permanent rupturing strains so often left in the product of the ordinary rail-rolling operation. Whenever the metal becomes clogged and jammed in its passage 105 through the train, or whenever it is desired to remove the upper rolls and sections of the housings of the horizontals, the inlet-valves of the hydraulics (or other lifts operated by fluid-pressure) are opened and the plungers are 110 forced up, imparting a vertical movement to the lifting-rods. This vertical movement of the lifting-rod swings the upper portions of the locking-clutches outward toward the sides of the housings, causing a reverse motion of their 115 lower ends, and withdrawing them from the rectangular slots formed in the upper part of the inner faces of the lower sections of the housings. As soon as the upper portions of the clutches swing until they are in line with the lifting-rods the full strain comes directly 120 upon the pivots of the clutches, and the upper sections of the housings are gradually elevated until they are removed to the height desired.

The operation of the verticals is as follows: 125 The adjusting-screws *e* are turned by hand to relieve the pressure of the side of the housings-caps upon the heads of the upper sections. The inlet-valves of the hydraulics (or other suitable lifts which may be employed) are 130 opened, and the plungers impart a direct upward movement to the lifting-rods, which, be-

ing attached to the housing-caps, raise them until they clear the heads of the housings, at which point the tops of the caps are forced against the cross-heads to which the crank-rods are attached, and by imparting a vertical movement to the upper ends of the crank-rods turn the cranks and swing the upper sections open upon the lower housing-section. In readjusting the horizontals into position it is merely necessary to close the inlet and open the outlet valves of the hydraulics, when the weight of the plunger and the upper housings will cause the latter to settle down into position, and the weight of the plungers will then force the lower ends of the picking-clutches into the rectangular slots in the inner faces of the lower sections of the housings, and thereby lock both the upper and lower sections together. In readjusting the verticals into position it is merely necessary to close the inlet and open the outlet valves of the lifts, when the weights attached to the cranks of the pivots will draw the upper sections of the housings again into position, and the plungers, descending, then cause the lifting-rods to force the housing-caps in position upon the heads of the housings.

The chief advantages of my invention are, first, blooms and piles are reduced into rails so rapidly that there is little or no perceptible difference between the temperature of the flange and head during the rolling operation; consequently perfect flanges can be produced; secondly, the web and flange of the rail may be altered, if desired, so as to more perfectly meet the conditions of the beam, as they can be rolled without cracking; third, the flanges may be made thinner, wider, and may be rolled without leaving permanent rupturing strains in the rail, as has heretofore happened from the ordinary mode of rolling, (see Holly on "Rail-Patterns," page 868, vol. 9, Transactions of American Mining Engineers;) fourth, qualities of iron and steel may be used that could not stand the ordinary rolling operation; fifth, the tendency of any shape of iron and steel to crack upon the edges—the portions which cool soonest—may be overcome; sixth, the rolls may be adjusted to give any desired degree of reduction at each pass that may be necessary in working different qualities of metal, whereas such an adjustment cannot be effected in the use of the ordinary method; seventh, the entire set of rail-rolls may be removed from the train and others inserted in their place in thirty minutes, whereas it requires at least two hours and one-half to change a set of ordinary rolls; eighth, the production is largely increased; ninth, all portions of the machinery are easily got at for removal, replacement, or repairs; tenth, better rails at a less cost are produced.

Having described my invention, what I claim, and desire to secure by Letters Patent, is—

65 1. The mode herein described for preventing flanges from cracking during the reduction

of the pile, bloom, or billet into the finished bar, which consists in arranging a series of sets of rail-rolls in close proximity to and in line with each other, so that several or all the sets may operate upon the metal at one and the same time, and then adjusting each set so as to throw a back-pressure of the metal upon the delivery side of the groove of the preceding set, substantially as and for the purpose herein set forth. 75

2. A continuous rail-train composed of a series of sets of rail-rolls journaled in and carried by sectional housings and provided with suitable mechanism for removing the upper sections and replacing them in position upon the lower, constructed and arranged to operate substantially as and for the purpose herein set forth. 80

3. The method of preventing the metal from cracking along its flanges or edges during its passage through a continuous train, which consists in adjusting the succeeding set or sets of rolls to reduce the metal to a sufficient degree at each pass or any pass to cause each set to deliver the metal a little faster than the succeeding set tends to receive it, whereby the metal is slightly "upset" during its passage from the delivery side of the preceding set to the entrance of the groove in the succeeding set or sets, substantially as and for the purpose herein set forth. 85

4. The method herein described for preventing the metal from cracking or tearing along its flanges or edges during its passage through a continuous mill, which consists in driving each successive set from the first at a little less rate of surface speed than that of the metal as it emerges from the delivery side of the preceding set of rolls, whereby tearing strains 100 upon it are avoided, substantially as and for the purpose herein set forth. 105

5. Housings for a set of vertical rolls, composed of two upper and a lower section pivoted together in such a manner as to allow the upper sections to swing separately and in opposite directions into and out of working position by means of their pivotal connection with the lower, constructed and arranged substantially as specified. 110

6. Housings for a pair of vertical rolls, composed of two upper vertical sections pivoted to a lower section and each carrying a vertical roll so arranged in relation to the upper sections as to participate in any motion imparted to the latter, substantially as and for the purpose herein set forth. 115

7. Housings for a set of vertical rolls, composed of two upper vertical sections, each pivoted to a lower housing-section, and provided with suitable actuating mechanism to impart a swinging lateral movement to the upper sections upon the lower, constructed and arranged substantially as and for the purpose herein set forth. 125

8. Housings for a set of vertical rolls, composed of two upper vertical sections, each pivot-

ed to a lower section, in order that the upper sections may swing upon the lower section, and provided with counter balances or weights, which are so arranged in relation to the upper sections as to cause the latter to swing back into position after having been opened, substantially as and for the purpose herein specified.

9. Vertical-roll housings composed of two upper sections, each pivoted to a lower section and provided with an adjustable detachable housing-cap, in combination with suitable mechanism for removing and replacing the cap and swinging the upper sections into and out of working position, constructed and arranged to operate substantially as and for the purpose herein set forth.

10. Vertical-roll housings having two upper vertical sections, each pivoted to and arranged to swing upon a lower section, which is provided with suitable driving-gear to actuate the rolls, the rolls and upper sections of the coupling-clutches being so arranged in relation to the upper sections of the housings as to allow them to participate in any movement imparted to the latter, constructed and arranged to operate substantially as and for the purpose herein set forth.

11. The combination of sectional roll-housings comprised of an upper vertical roll carrying sections and a lower housing-section with a hydraulic lift, or its equivalent, and suitable intermediate connecting devices to open or remove the upper sections of the housings, together with the roll journaled therein, by the action of the lift, constructed and arranged to operate substantially as and for the purpose herein set forth.

12. Sectional housings for horizontal rolls, separable at or near a plane passing between the working-faces of the rolls, and provided with locking-clutches, in combination with a hydraulic or equivalent lifting device, and intermediate connecting mechanism to adjust the locking-clutches into and out of position and to remove and replace the upper sections of the housings, constructed and arranged substantially as and for the purpose herein specified.
